UNITED STATES PATENT OFFICE.

HENRY V. MORIN, OF POUGHKEEPSIE, NEW YORK.

TOOL-HOLDER.

1,395,859.

Specification of Letters Patent.

Patented Nov. 1, 1921.

Application filed December 2, 1920. Serial No. 427,795.

To all whom it may concern:

Be it known that I, HENRY V. MORIN, a citizen of the United States, residing at Poughkeepsie, in the county of Dutchess and 5 State of New York, have invented certain new and useful improvements in a Tool-Holder, of which the following is a specification.

This invention relates to improvements 10 in holders for boring tools for enlarging cavities previously bored, and has for one of its objects to simplify and improve the construction and increase the efficiency and utility of devices of this character.

15 Another object of the invention is to provide a device of this character in which the tool may be adjusted for different sizes of cavities without the necessity of employing a wrench or other extra tool or implement.

20 With these and other objects in view, the invention consists in certain novel features of construction as hereinafter shown and described and specifically pointed out in the claims, and in the drawings illustrative of 25 the preferred embodiment of the invention.

Figure 1 is a side elevation of the improved device.

Fig. 2 is a front elevation.

Fig. 3 is a side view with the body or head 30 in section on the line 3—3 of Fig. 2.

Fig. 4 is a front elevation with the cap removed and the holding head and holder partly in section.

Fig. 5 is a detached perspective view of 35 the tool holder.

Fig. 6 is a section of the holder and thrust block.

The improved device includes a body or head 10 preferably cylindrical externally 40 and with the outer surface knurled or otherwise roughened to enable it to be gripped by the hand of the operator.

At its outer end the head 10 is formed with an internally threaded recess 11 concentric to its exterior, and formed in the head is a relatively large recess 12 eccentric to the exterior of the head and communicating with the concentric recess.

The remaining portion of the head is 50 counterbored with annular steps 13 concentric to the exterior of the head and eccentric to the recess 12.

Fitting in the recess 11 is an externally threaded disk 14, the latter having sockets 55 15 to receive the turning pins of a pin

wrench to enable the disk to be inserted and removed.

The disk 14 is also provided with a central aperture 16 from which an enlargement 17 extends at one side.

60 The concentric portion 16 of the aperture is undercut as shown at 18 forming an internally directed bearing, as shown.

Mounted for rotation in the concentric stepped bore of the head 10, is a stock or 65 shank comprising a socket engaging portion 19 and a plurality of annular enlargements 20 conforming to and engaging the shoulders 13, of the head.

The member 19—20 extends at 21 into the 70 eccentric recess 12, the portion thus extended being provided with a transverse guideway having inwardly facing guide channels 22 in its side walls. At their outer ends the sides of the portions 21 are further extended and provided with segments 24 to fit into the concentric portion 18 of the opening in the disk or holding washer. The segments 24 serve as bearings to support the outer end of the member 21.

75 Slidably disposed within the guideway defined by the extension 21 of the stock is a tool holder represented as a whole at 23 and having guide ribs 25 engaging in the guide channels 22. The member 23 is provided with an internally threaded socket 26 at one 80 side of its center to receive the threaded terminal of the tool, indicated at 27.

85 At its inner end the socket 26 is reduced and extended through the body of the holder 90 to receive a threaded locking stud 28 having an enlarged inner end or head 29 against which the inner end of the tool stock 27 impinges when the latter is screwed "home" in the holder.

95 The member 28—29 serves as a means for holding the tool 27 in adjusted position longitudinally, and likewise as a locking means to prevent the displacement of the tool.

At one end the member 23 is curved, as shown at 30, to conform substantially to and 100 rotative in the eccentric recess 12.

Formed in the other end of the holder 23 is an outwardly opening slot and slidably engaging in the slot is a thrust block 31.

105 Formed in the inner face of the block 31 are sockets to receive springs 32, the springs bearing against the inner end of the slot in the member 23 and operating to maintain 110

the block yieldably locked in adjusted position against the adjacent wall of the recess.

The block 31 is provided with an elongated aperture 33 to receive a pin 34 extending through the walls of the member 23, to prevent the block from being detached when the holder is removed, while at the same time permitting the requisite movement under the influence of the springs 32.

10 Engaging upon the outer enlargement of the stock 19 and attached for rotation therewith by a key 35 or other suitable means, is an annular member 36 having marginal graduations 37 coacting with corresponding graduations 38 on the head 10, as shown.

15 The improved device is designed for use in accurately enlarging holes or cavities already bored, and to this end the cutting portions 39 of the tool is disposed laterally 20 of the body or stock 27.

25 By this construction it will be obvious that by rotating the head 10 in one direction upon its seats 20, the holder 23 will be forced to move in the slot in the portion 21 by reason of the engagement of its terminals 30 and 31 with the eccentric bore 12, the extent of this movement being controlled by the size of the bore 12. The bore 12 is so arranged that when the holder 23 is at one 35 end of its stroke, the tool 27 will be in alignment with the stock 19, and the device may then be employed to hold a simple drill. Then when the position of the holder is reversed, the cutting edge 39 will be at its greatest distance from the axial line of the stock 19 and will cut its largest sized cavity. The implement may be adjusted to cut any required size of cavity by setting the member 10 at a corresponding point by actuating 40 the member 36 as will be obvious.

The vernier device 37 and 38 enables the sizes to be cut to be accurately "gaged."

45 The improved implement is simple in construction, can be inexpensively manufactured and of any required size and capacity, and any required size or range of tool may be employed.

50 The preferred embodiment of the invention is disclosed in the drawings and set forth in the specification, but it will be understood that any modifications within the scope of the claimed invention may be made in the construction without departing from the principle of the invention or sacrificing 55 any of its advantages.

I claim:

1. A device of the class described comprising a head having a concentric bore and

with a recess eccentric to the bore and communicating therewith, a shank rotatively 60 engaging the bore and extending into the recess, and a tool holder supported movably by the shank within the recess and movably engaged by the walls of the same.

2. A device of the class described comprising a head having a concentric bore and with a recess eccentric to the bore and communicating therewith, a shank rotatively engaging the bore and extending into the recess, said extended portion having a transverse guideway, and a tool holder supported 70 movably within the guideway and movably engaged by the walls of the recess.

3. A device of the class described comprising a head having a concentric bore and with a recess eccentric to the bore and communicating therewith, a shank rotatively engaging the bore and extending into the recess, said extended portion having a transverse guideway, a tool holder supported 75 movably within the guideway and movably engaged at one end by the wall of the recess, and a thrust block spring supported at the other end of the holder and bearing yieldably against the wall of the recess. 80

4. A device of the class described comprising a head having external graduations and a concentric bore and with a recess eccentric to the bore and communicating therewith, a shank rotatively engaging the bore and extending into the recess, a tool holder supported movably by the shank within the recess and movably engaged by the walls of the same, and a member rotative with the shank and having graduations 95 coacting with the graduations on the head.

5. A device of the class described comprising a head having external graduations and a concentric bore and an eccentric recess communicating with the bore, a shank 100 member rotatively engaging in the bore and having a slotted extension projecting into the eccentric recess, a holder member engaging in the slot and having a socket adapted to receive a tool stock, said tool stock being 105 disposed in alignment with the shank when the holder is in one position, a holding disk engaging in said head and provided with an opening concentric with the shank and with a lateral enlargement, and through which 110 the tool extends, and a member rotative on the shank and graduated to correspond to the graduations on the head.

In testimony whereof I affix my signature hereto.

HENRY V. MORIN.
